US00D571479S

(12) **United States Design Patent**
Wagner

(10) **Patent No.:** **US D571,479 S**
(45) **Date of Patent:** **** Jun. 17, 2008**

(54) **RED MIXING TIP SHAFT**

(75) Inventor: **Ingo W. Wagner, Woerthsee (DE)**

(73) Assignee: **3M Innovative Properties Company,**
St. Paul, MN (US)

(**) Term: **14 Years**

(21) Appl. No.: **29/224,548**

(22) Filed: **Mar. 3, 2005**

(30) **Foreign Application Priority Data**

Sep. 20, 2004 (EM) 000228275-0001

(51) **LOC (8) Cl.** 24-02

(52) **U.S. Cl.** D24/220

(58) **Field of Classification Search** D24/216-230;
222/145.6; 366/602, 318, 320, 339, 336,
366/181.5; D7/379

(57) **CLAIM**

The ornamental design for a red mixing tip shaft, as shown and described.

DESCRIPTION

FIG. 1 is a perspective view of red mixing tip shaft showing my new design;

FIG. 2 is a front elevation view thereof, the rear elevation view being identical;

FIG. 3 is a side elevation view thereof, the other side being identical;

FIG. 4 is a top plan view thereof; and,

FIG. 5 is a bottom plan view thereof.

The drawings are lined for color. The following explanation of the color is provided for clarity. The lining in all views represents red.

1 Claim, 1 Drawing Sheet
